UNITED STATES PATENT OFFICE

KARL MUTTER, OF TRIPDIS, GERMANY

LOOM

Application filed April 28, 1930, Serial No. 448,071, and in Germany May 2, 1929.

This invention relates to improvements in looms and more especially to an improved construction of loom for plain weaving. Essentially my invention consists therein that 5 shuttles are used which, instead of being thrown freely over the width of the fabric through the shed, are moved through a fixed guide-means. The advantage resulting from this construction resides in the fact that, 10 while heretofore only single shuttles could be thrown at a time over the width of the fabric, by my invention it will be possible to operate a plurality of shuttles in immediate succession, so that the shuttles will continuously be in operation. 15

An example of a preferred construction of a loom according to my invention is shown in the accompanying drawings and described in the below specification, while the novel 20 combinations of parts are pointed out in the appended claims.

In the drawings, Fig. 1 is a diagrammatical representation, partly in section, of a preferred form of construction of my new loom, 25 said section being taken in longitudinal direction of the warp-threads, Fig. 2 a diagrammatical side-view of the loom shown in Fig. 1, Fig. 3 a plan-view showing in particular a plurality of shuttles used in the loom according to my invention, Fig. 4 is a diagram 30 explaining the actuation of the shed by means of the shed actuating rollers shown in Figs. 1 and 3, and Fig. 5 a cross-section through the shaft of the weaving roller of the loom.

Referring more particularly to the drawings in which like reference characters designate like parts, it may be noted that only so much of the loom is shown as necessary to give a clear picture of the novel construction 40 of the loom and the principles of operation according to my invention. Thus, for instance, the thread-guards which are of subordinate importance in connection with my invention are omitted; the thread-guards, 45 moreover, may be replaced by any one of the auxiliaries which are known in connection with looms of ordinary construction. Further details which are evident to those skilled in the art are likewise omitted from the drawings, such as for instance, the governor for

the beam for the completed fabric, the brake for the warp-beam and so forth, as these parts may likewise be constructed in any manner usual in the construction of looms.

The main frame of my new loom is composed of two side-walls R, which are connected with each other by means of channel-irons E and F to provide a proper re-inforcement. Auxiliary bars G and H of suitable construction are used as a supplementary reinforcement for the frame and bearing blocks or pedestal carriages which are omitted from the drawings for the sake of clearness serve for the reception of the shafts which carry the main operating members of the loom. 55

K is the warp-beam on which the warp-threads 15 are wound. The latter are passed over the cloth-beam C and from here through the dividing grooves on the cross-rails k and the harness A which is more fully described hereinbelow. The warp-threads are thereupon further carried over the breast-beam B towards the cloth-roller or beam W for the completed fabric. The warp-beam and the beam for the completed fabric are driven in 70 the usual manner. 75

The weaving mechanism proper of my new loom comprises substantially four shafts 1, 5, 26 and 33. The weft-threads are operated by the shaft or weaving roller 1, while the motion of the shuttles is effected by the shaft 5 (feed-shaft). The harness which serves for the formation of the shed is operated by the treadle-shaft or shed actuating shaft 26. The shaft 33, finally, serves for a special purpose 80 more fully explained hereinbelow. The several shafts are connected with each other by suitable gears whereby all shafts are operated from a single shaft. Preferably the drive is derived from the shaft 5 and a loose and a 85 fixed pulley S and S₁ is used on the shaft 33. If the driving belt (not shown in the drawings) which serves for driving the loom is laid on said fixed pulley, rotary motion will be transmitted from the shaft 33 to the shaft 90 5 by way of a gear 34 and a further gear 35 mounted upon said shaft 5. The shaft 5 furthermore carries a gear 36 which meshes with a companion gear 37 on the shaft 1. Rotation 95 of this shaft is transmitted by a gear 38 and 100

an intermediate gear 39 to a gear 40 mounted upon the shaft 26.

The shaft 33 drives by means of a gear 41 and an intermediate gear 42 a further gear 43 connected with a worm 44 in mesh with a worm-gear 45. The shaft 46 of this worm-gear 45 carries a disk 31. It is to be understood that while the disk 31 is mounted on the shaft 46, as shown in Fig. 2, a second disk 30 is provided on the other end of the machine and this second disk is mounted on a second shaft 46 with worm drive identical to that indicated at 44-45. Therefore, in Fig. 1 two shafts 46 and the two disks 30 and 31 lie one 15 behind the other.

In order to produce a plain binding, the ratio of gear between the shafts 33 and 5 is 1:1, the ratio of gear between the shafts 5 and 1 is 2:1 and the ratio of gear between the 20 shafts 1 and 26 is likewise 2:1.

For tweel binding there are provided two shed actuating or treadle rollers, the ratio of gear between the shafts 1 and said rollers being now 4:1. The governor for the beam for 25 the completed fabric is preferably operated from the shaft 1. As regards its specific construction this governor is similar to governors of this kind which are ordinarily used in connection with looms.

30 The weaving roller is operated by means of cam-disks 2 of any desired shape upon the shaft 1 by the intermediary of spacing members in the form of further disks 3. In this manner, for instance, it will be possible, as 35 may be seen from Fig. 1, to make the several cam-disks of oblong shape and to angularly displace said disks with respect to each other to form a kind of threaded shaft as shown diagrammatically in Fig. 3. This displacement of the cam-disks now will have the effect that one portion of said disks will contact at 40 a time immediately with the completed fabric, while the intermediate disks will be positioned at some greater distance from the completed fabric or, as the case may be, from the 45 last operated weft-thread and the circumference of the disk.

Upon rotation of the shaft 1 consequently the weft-thread operated by the shuttle 13 50 will be engaged and thrown-in quite gradually.

In accordance with the specific kind of fabric to be woven on the loom the form of the disks 2 may be properly chosen. The 55 disks, moreover, may be of a conformation permitting to effect not only a single but also a double beat. Thus, the disks shown in full-drawn lines in the drawings serve for producing a single beat, while an alternate conformation of the disks as shown in dash-dotted lines may serve for producing a double beat. Finally, also disks may be used which provide a proper guide for both, the upper as well as the under warp-thread.

60 65 The shuttles may be of any construction

having, for instance, the form of a long bolt 12 on which there is mounted—either loosely or fixedly—a thread-spindle or spool 13 which is wound-off automatically and causes the weft-thread 14 to pass through a special 70 guide 14a as far as to a point above the center of the shaft 1, so that the weft-thread may now be engaged in the front of the guide 14a by the disks 2. The bolt 12 as well as the guide 14a are mounted upon a base-plate 11 75 of sheet metal. This plate or sheet 11 carries a downwardly directed arm 11a and is connected by the means of an oval intermediate member with a slide 11 having the conformation of a dovetail. The plate or 80 sheet 11 serves to secure the guide by acting against a comb 33b fixed to the frame 8 by means of a cross-bar 33a.

The frame 8 consists essentially, as shown in Figs. 1, 2 and 3, of a series of vertical bars 85 and spacing disks 9 mounted on transverse rods 9a. Free spaces or interstices will thus be provided in the frame permitting passage of a number of warp-threads as shown at 15 and 15a in Fig. 3. In the vertical bars of the frame 8 there is provided a guide means for the dovetail of the slide 11b, as may likewise be seen from Fig. 1.

90 The arm 11a engages with a shaft 5 composed of a plurality of disks 7. The several disks 7 in the present case are likewise separated from each other by spacing disks 6 similar to the spacing disks 3 on the shaft 1. The displacement of the disks 7 is of such character that there will be produced a worm 95 having a very small pitch, said worm during rotation moving the shuttle over the width of the fabric, as shown in Fig. 3. The shuttle may be introduced by hand or also automatically. The same holds true for the shuttle 100 during its motion away from the other edge of the fabric.

105 Fig. 2 shows an automatic operation of the aforementioned kind. The shuttles, after having been thrown by the shaft 5 over the width of the fabric, are moved towards a closed guide 47 in which a disk 31 rotates, as indicated at the top of Fig. 2. Recesses 49 are provided at the circumference of the disk, the size of said recesses being in agreement 110 with the size of the intermediary member 11c. These recesses 49 now grip the shuttles at the intermediary part 11c and move said shuttles together with the disk along the closed guide groove 47 towards above, where they will 115 come in engagement with a guide-groove 48. The above mentioned shaft 33 carries a worm 28, preferably made of a single piece having the same pitch as the worm 7 on the shaft 5. The arm 11a will now be gripped by the worm 120 and the shuttle moved over the fabric towards the other edge thereof. At this place there are provided a disk 30 identical with the disk 31 and a guide 47 by means of which 125 the shuttles are again carried into the guide 130.

or frame 8 and into the range of action of the worm 7.

After winding-off the spool 13 must be replaced. For this purpose the time may be used during which the shuttles are moved back by the shaft 28. Owing to the fact that the operation of weaving is carried out simultaneously with several shuttles thrown across the fabric, the motion of the shuttles is so slow that replacement of a spool will be immediately possible.

Whenever the weft-threads are thrown across the fabric, they will be cut-off automatically. There are two possibilities of such cutting-off of the weft-threads. In the breast-beam there may also be provided a knife 29a as shown in Fig. 2 and the last of the disks 2 may be constructed as a knife-disk 29. In this case there is provided a special possibility of cutting-off the weft-thread after the shuttle has been moved further through a certain distance by the feed-roller 5. In the last case the weft-threads will terminate immediately at the edge of the fabric, while in the first case they are laid around and properly woven into the fabric. The weft-threads also may be connected with the warp-threads by means of a glue, paste or the like.

After cutting off the weft-thread, the latter will suspend to some length from the shuttle, as clearly shown in Fig. 1. Since the several weft-threads are always cut off uniformly by the cutting device, said weft-threads will also uniformly suspend from all shuttles. During being thrown into the shed from the left-hand side thereof, the shuttle will drag this end of the weft-thread along and as the shed closes shortly in the rear of the shuttle, said weft-thread will also be properly caught to form a smooth edge on the fabric, the same as on the left-hand side. If it is desired to produce an especially strong and sharp weaving edge of the fabric, a cutting device with knives in the form of bars may be provided, both, on the left-hand side as well as on the right-hand side of the fabric.

The shed is formed by heddles 16 as may be seen from Figs. 1 and 2.

The shed actuating roller consists of a shaft 26 on which rings 27 and disks 25 are arranged in alternate succession. The latter constitute the shed actuating mechanism proper which, as indicated in Fig. 2, is made up from segments. The shed actuating disks are displaced relatively to each other similarly to the disks on the above described shaft, so that a threaded spindle or the like will be produced. Every shed actuating disk co-operates with an annular member 24 and a lever 20 pivoted thereto. The front ends of the levers 20 are provided with a bore 20a engaged by the strings 19 by the aid of eyes 21 and 22. The strings 19 again are connect-

ed by means of the eyes 17 with the heddles 16 which form the shed. In this manner, several systems will be formed which run over the rollers 18 and 18a. Upon rotation of the shed actuating roller 26 the levers 20 will be rocked upward and downward around the fixed pivot point 23, the disks 25 carrying the annular members 24 with them. Motion of the lever 20 will now likewise cause upward and downward motion of the strings, so that alternately the warp-thread 15 is lifted and at the same time the warp-thread 15a lowered, and the warp-thread 15a lifted and the warp-thread 15 lowered in the one or other limit position of the lever 20.

Motion of the warp-threads 15 and 15a in this vertical position is rendered possible by the fact that both shafts or rollers 1 and 5 are provided with a plurality of spaced disks.

Owing to the displacement of the disks 25 on the shaft 26 there will be obtained a shed which progresses over the width of the fabric. A diagram of Fig. 4 shows the formation of the shed. A shed actuating lever 20, however, will not only actuate a single heddle but, if necessary also two heddles or finally also a whole bundle of such heddles which are connected in every case by means of the heddle carrier in the string 19. For plain fabrics, that is fabrics with a binding in the form of linen, one shed actuating roller will be sufficient. However, there may also be used a plurality of such shed actuating rollers simultaneously, only one series of heddles being now moved by each of these rollers. In case of a tweel-binding preferably two or four shed actuating rollers may be used. In case of a linen binding the pitch of the shed actuating roller is twice as large as that of the weaving roller. When using another binding, however, a shed actuating roller must be used having a pitch different from the former.

During one rotation of the weaving roller, the feed roller 5 will move a shuttle 11 from the point *a* towards the point *b*, as shown in Fig. 3. The shed actuating roller 26 will also displace the periods of opening of the shed to the same extent by making one and one half revolution and in case of tweel-binding one and a quarter revolution.

The feed roller 5 may likewise be used in connection with ordinary looms and may be provided within the shuttle-race. The dovetail guide would in this case have to be replaced by a second feed roller positioned either above or below the first feed-roller. In some cases of course also one feed roller may be sufficient, if proper guiding of the shuttle can be effected. Instead of the plates or sheets 8 a reed would in this case have to be used. With a loom equipped in this manner one or more widths of fabrics may be woven according as to whether the shed actuating roller is rotated a greater or smaller num-

ber of times in left-hand or right-hand sense of rotation. The picker mechanism and shuttle-boxes may in this case be dispensed with. In other respects a loom of this construction operates in the same manner as a loom of ordinary construction.

5 I claim:

1. In a loom, a frame, a plurality of shuttles movable in said frame, means for throwing the shuttles in continuous succession over the width of the fabric, shed forming members, means to actuate the shed forming members to form a shed in advance of the moving shuttles over the width of the fabric and to close the shed behind said shuttles, the shuttle throwing means and the actuating means for the shed forming members being of substantially helical form to time the movements of the shuttle throwing means and the actuating means for the shed forming members.

10 2. In a loom, a frame, a plurality of shuttles movable in said frame, means for throwing the shuttles in continuous succession over the width of the fabric, shed forming members, means to actuate the shed forming members to form a shed in advance of the moving shuttles over the width of the fabric and to close the shed behind said shuttles, and a rotary cam-like beater operating in timed relation to the shuttles and shed forming members to beat the weft thread during closing of the shed, the shuttle throwing means and actuating means for the shed forming members and weft beater being of substantially helical form.

15 3. In a loom, a frame, a plurality of shuttles, guide means for the shuttles, and means for throwing the shuttles in continuous succession over the width of the fabric, each shuttle including a spindle, a bobbin thereon, supporting members carried by the spindles and mounted in the guides, a projecting arm on the supporting member provided with 20 guiding eyes for the weft thread, said guide means being arranged to guide the shuttles through the shed and externally thereof.

40 In testimony whereof I have signed my name to this specification.

45 50 KARL MUTTER.
